UNITED STATES PATENT OFFICE.

ANTHONY BORSELLA AND CELESTE SOCCOL, OF NEW YORK, N. Y.

AUTOMATIC SELF-STARTER.

1,082,927.

Specification of Letters Patent. Patented Dec. 30, 1913.

Application filed April 3, 1913. Serial No. 758,700.

To all whom it may concern:

Be it known that we, ANTHONY BORSELLA and CELESTE SOCCOL, citizens of the Kingdom of Italy, and residents of the city of New York, in the county of New York and State of New York, have invented a certain new and useful Automatic Self-Starte, of which the following is a specification.

Our starter is of special value in connection with gasolene engines, as, for example, engines used in automobiles, motor-boats, etc. It is, however, not limited to such uses, but may be applied in connection with any purpose requiring the use of gas under pressure, as for example, to feed gasolene to the carbureter, etc.

The general object of our invention is to provide a mechanism, of the character indicated, which will be simple in construction, and easy to actuate, and which will be positive and reliable in operation.

With these objects in view, and others appearing as the specification proceeds and the nature of the invention more fully appears, the invention comprehends, generally stated, mechanism for storing up a part of the energy developed by the engine when running; and mechanism for releasing such stored energy in a manner that will start the engine.

In the accompanying drawings, we have, as an example, shown one form of embodiment of the invention capable of carrying out the underlying principles thereof, and in these drawings, in which like reference-characters denote corresponding parts throughout the several views: Figure 1 is a side elevation of our mechanism, its position relative to an automobile being indicated by a skeleton outline of the framework of the latter; Fig. 2 is a fragmentary view, in rear elevation, of the automobile dashboard, showing the controlling-valve and the storage-tank gage positioned on the dashboard; Fig. 3 is a fragmentary detail view, in central longitudinal section, of the distributing valve and its casing, and its connection with the shaft which is driven, through gearing, by the engine-shaft; Fig. 4 is a front end view of the distributing-valve, the connecting pipes being shown in section; Fig. 5 is a detail view of the distributing-valve, removed from its casing; Fig. 6 is a fragmentary detail view, in central vertical section, of the dashboard- or storage-tank valve; Fig. 7 is a section on

the line 7—7, Fig. 6; Fig. 8 is a sectional detail view of the valve used on all of the cylinders, except the end one; Fig. 9 is a sectional view of the special valve used on the end cylinder.

Referring, now, in detail to the drawings: The engine is of the well-known four-cycle type, in which a mixture of gas and air is drawn into the cylinders, compressed and exploded or fired by means of an electric spark. The engine-cylinders are designated 50, 50, 50, and 51.

The end cylinder 51 carries a valve-casing 11 (see particularly Fig. 9), provided with a threaded lower end 36 screwed into the top of the cylinder. The valve-casing 11 is also provided with a longitudinal bore or port 36 communicating with the compression-space of the cylinder 51, and having branches 32 and 34 extending through arms 32^a, 34^a carried by said valve-casing, the branch 32 and arm 32^a being upwardly inclined relative to the bore 35, and the branch 32 being of larger cross section than that of the branch 34 or the bore 35. The upper portion of the bore 35, which is designated 35^a, is also of larger cross section than that of the latter. The branch 32 constitutes a raceway or runway for a check-valve, in this instance a ball valve 31, which is normally seated at the rear end of the branch 34, shutting off communication or passage therethrough. A check-valve, in this instance a ball-valve 37, is also disposed in the upper portion 35^a of the port 35, and has a seat at the lower end of said portion 35^a, as shown in Fig. 9. The branch 32 is closed, at the upper end thereof, by a screw-cap 33; by removing which, access may be had to the ball 31.

Registering with the upper end of the port 35 is one end of a pipe 15, leading to a dashboard- or storage-tank valve (hereinafter particularly to be described). Registering with the outer end of the branch 34 is a pipe 7, leading to a distributing-valve (also hereinafter particularly to be described). The pipes 15 and 7 are provided, at their ends, with annular flanges 15^a and 7^a, respectively, which are clamped, respectively, to the upper end of the casing 36 and the outer end of the arm 34^a by union-nuts 34^b, 34^c, whereby the pipes are held firmly in position, against movement. The simple means shown for connecting the pipes to the valve-casing permits of easy assembly, and

affords a ready means of detachment, should it become necessary, for purpose of repairs.

Carried by each of the three cylinders 50, 50, 50 is a valve-casing 36^a, which is similar to the valve-casing shown in Fig. 9, excepting that the ball-valve 37 and the pipe 15 shown in connection with the valve-casing of Fig. 9 are omitted. The valve-casing 11^a shown in Fig. 8 contains but a single ball-valve 31, and but a single pipe (as 6, 8 or 9, Fig. 1) communicates with said casing, this pipe (6, or 8, or 9, as the case may be) leading to the distributing-valve, hereinafter to be described.

15 In use, the check-valves 31 are kept on their seats by the force of the compression and explosion, and maintain the pipes 6, 7, 8 and 9 out of communication with the cylinders 50, 50, 50 and 51.

20 The valve 37 opens and permits passage of gas from the cylinder 51 through the pipe 15 when the dashboard-valve (about to be described) is moved in a manner hereinafter appearing.

25 The distributing-valve comprises, in this instance, a disk 23 provided with an arcuate, eccentrically-disposed slot or port 23^a, and with a concentrically-disposed stem 24 annular in cross section, and projecting 30 through a bearing 4^a (in this instance, truncated-cone shaped) carried by a boxlike casing 4. The stem 24 terminates, at its outer end, in a head 24^a, of a shape other than circular in cross section, fitting a correspondingly-shaped recess in a coupling-member 25 secured, in any suitable manner, as by a screw 25^a, to a gear 26 fast on a shaft 2. Said gear 26 meshes with a gear 26^a on the engine-shaft, whereby the distributing-valve 23 is rotated.

40 The casing 4 is closed by a cover 24^b carrying outward-projecting exteriorly-threaded nipples 4^c, 4^c, 4^c, 4^c, having interior, longitudinally-extending ports 4^d therethrough. The ends of the pipes 6, 7, 8 and 9 are secured to the nipples 4^c by screw-caps 4^e. The four ports 4^d are arranged symmetrically, as shown in Fig. 4, so that, as the valve 23 revolves, its port 23^a will 45 register with each port 4^d successively. These ports 4^d, communicating with their respective pipes 6, 7, 9 and 8 (as shown in Figs. 1 and 4) are arranged in the order of firing of the charges in the cylinders.

50 In other words, in the operation of the valve 23, the gas is fed through the port 23^a to the pipes 6, 7, 9 and 8, in the order named. The casing 4 also carries an additional, exteriorly-threaded, outward-projecting nipple 4^f, having a longitudinal, interior port 4^g extending therethrough and communicating with the interior of the casing 4. A feed-pipe 5 communicates with this port 4^g and is clamped to the nipple 4^f by a union-nut 4^h.

The dashboard- or storage-tank valve consists, in this instance, of a hollow, rotatable member or plug 18 (see particularly Figs. 6 and 7), annular in cross section, and seated in a valve-casing 30 secured, in any suitable manner, to the automobile - dashboard 29. Said valve is provided with two ports 27 and 28 spaced apart from each other a suitable distance, in this instance one-fourth of the circumference of the valve. The valve-casing 30 carries three exteriorly-threaded, outward-projecting nipples 30^a, 30^b, 30^c, with which are respectively connected, by union-nuts 30^e, pipes 15, 16 and 5. The nipples 30^a, 30^b, 30^c are provided with interior, longitudinally-extending ports 44. In the position of the parts shown in Fig. 7, the valve 18 is shown connecting the pipes 15 and 16, so that the motor will pump compressed gas and air from the end cylinder 51 into the storage-tank 21, with which the pipe 16 communicates (as shown in Fig. 1). A gage 22 connected and communicating with the pipe 16 is provided, to indicate the pressure in the tank 21. The valve 18 is also provided with a stem 18', to which a crank 19 is secured, and whereby said valve may be operated and controlled. When the crank 19 is turned so as to move the valve 18 one-fourth of a revolution, the 95 ports 27 and 28 will register, respectively, with the ports of the nipples 30^b and 30^c, so that the pipes 16 and 5 are connected, and, thereby, gas is permitted to flow from the tank 21 to the distributing-valve 23, and, thence, to one of the cylinders. Of course, the valve 18 may be rotated or revolved, so as to blank all three of the ports 44; such result being effected by rotating the valve more than a half revolution from the position shown in Fig. 7.

The casing 30 of the dashboard-valve 18 is connected by the wire 38 (see Fig. 1) to one terminal of the ignition-coil 37. A button 20 is carried by the dashboard 29, in the path of movement of the crank 19, and a wire 39 connects the terminal 20 with the sparking-plug 43 on top of the cylinder 51; so that, when the crank 19 is turned to the starting position, contact between the casing 30 and the button 20 is established by said crank. Wires 40, 41 and 42 connect the spark-plugs 43 on top of the cylinders 50, 50, 50 to the coil 37 in the usual manner. It will be apparent, therefore, that the dashboard-valve, in addition to turning the compressed gas into the engine, also automatically establishes, at the same time, the ignition to the cylinder 51, from which it was disconnected when the compressing in the storage-tank 21 was in progress. When the tank 21 is connected to the end cylinder 51 by movement of the dashboard-valve 18, for the purpose of compressing gas in the storage-tank, the dashboard valve 18 is in such 12

position that the ignition is disconnected from this particular cylinder, and, hence, every time the piston compresses an explosive charge of gas and air in the cylinder 51, 5 it is expelled past the check-valve 37 and through the pipe 15 into the dashboard-valve 18, thence through the pipe 16 into the storage-tank 21. The crank 19 of the dashboard-valve 18 is now turned to running position, and, thereby, the ignition is automatically connected by such act with the cylinder 51, which has been used for charging 10 the gas into the storage-tank 21. The engine is now operating in the ordinary manner, and may be used thus as long as desired.

After the engine has been stopped, and it is desired to start again, the crank 19 of the dashboard- or storage-tank valve 18 is 20 turned to starting position. The compressed mixture now passes through this valve 18, by means of the pipes 16 and 5, to the distributing-valve 23, and through the port 23^a thereof, and, thence, to the cylinder which has its piston on the working or firing stroke. The gas mixture, thus admitted, starts to move the piston downward, 25 rotating the engine-shaft and through the contact-device connects it to the battery or magneto and fires the charge. This gives a 30 sudden impulse of sufficient power to spin the fly-wheel and carry it over the "center" and compress gas in the next cylinder in order, and thus the cycle of the engine is 35 established. The engine may now continue to run this way, or the crank 19 on the dashboard valve 18 may be turned to the position where the end cylinder 51 is disconnected from the ignition apparatus, but is connected to the storage-tank 21, and acts as a 40 compressor, to charge the gas into the storage-tank.

From the above description, taken in connection with the drawings, the many advantages of our invention will be obvious, 45 especially to those skilled in the art to which the invention appertains.

We are aware that many modifications in detail may be resorted to; but all such as 50 come within the scope of the appended claims, fall strictly within the scope and purview of the invention, and constitute no departure from the spirit thereof.

It may be mentioned that the cylinder 51 and the storage-tank 21 are of great commercial value in many ways. For instance, 55 said cylinder 51 or storage-tank 21 may be connected up with a tire-pump, for pump-

ing-up tires. The compression of the gas in the reservoir 21 can be raised to such an extent as to start any motor of any construction or power. By the use of the cylinder 51 and reservoir 21, and by raising the pressure in the latter sufficiently, the use of a double-firing magneto will be rendered unnecessary.

Having thus fully described our invention, what we claim as new and desire to secure by Letters Patent of the United States is:

1. In starting mechanism for automobiles, etc., a storage-tank; a plurality of engine-cylinders for the compression and explosion therewithin of an explosive mixture; means affording communication between 70 said storage-tank and one of said cylinders, including a storage-tank valve for controlling communication through said means; a distributing-valve; means affording communication between said distributing-valve 75 and said cylinders; means affording communication between said distributing-valve and said storage-tank valve; and ignition-mechanism for the cylinder which communicates with said storage-tank, said ignition-mechanism being controlled by said storage-tank valve.

2. In starting mechanism for automobiles, etc., a storage-tank; a plurality of engine-cylinders for the compression and explosion therewithin of an explosive mixture; 90 means affording communication between said storage-tank and one of said cylinders, including a storage-tank valve controlling communication through said means; a distributing-valve; means affording communication between said distributing-valve and 95 said cylinders; means affording communication between said distributing-valve and said storage-tank valve; and ignition-mechanism 100 for the cylinder which communicates with said storage-tank, said ignition-mechanism being controlled by said storage-tank valve so as to be inoperative or disconnected when 105 said storage-tank valve is moved to throw said cylinder into communication with said storage-tank.

Signed at the city of New York, in the county of New York and State of New York, this 15th day of March, A. D. 1913.

ANTHONY BORSELLA.
CELESTE SOCCOL.
